UNITED STATES PATENT OFFICE

ANDREW WEISENBURG, OF BALTIMORE, MARYLAND, ASSIGNOR TO CROWN CORK & SEAL COMPANY, INC., OF BALTIMORE, MARYLAND, A CORPORATION OF NEW YORK

DESIGN FOR A CLOSURE CAP

Application filed February 4, 1931. Serial No. 38,547. Term of patent 14 years.

To all whom it may concern:

Be it known that I, ANDREW WEISENBURG, a citizen of the United States, residing at Baltimore, State of Maryland, have invented a new, original, and ornamental Design for Closure Caps, of which the following is a specification, reference being had to the accompanying drawings, forming a part thereof.

Figure 1 is a perspective view of a cap showing my improved design and Figure 2 is a top elevation.

The dominant feature of applicant's cap resides in a top ring and a skirt, the skirt

having facets tangent to the ring and spaced apart by convex arcuate columns defined by grooves, each column and adjacent facets bevelled to form a plurality of spread wing portions about the cap below the top ring, and merging into the vertical wall of the top ring, with the tips of the wings defined by the points of tangency of the facets with the ring.

I claim:

The ornamental design for a closure cap, substantially as shown and described.

ANDREW WEISENBURG.
